(57) **CLAIM**

The ornamental design for a liquid transfer device with integral vial adapter.

DESCRIPTION

FIG. 1 is a front perspective view of a liquid transfer device with integral vial adapter in accordance with our new design;

FIG. 2 is a front elevational view thereof;

FIG. 3 is a rear elevational view thereof;

FIG. 4 is a right side elevational view thereof;

FIG. 5 is left side elevational view thereof;

FIG. 6 is a top plan view thereof; and,

FIG. 7 is a bottom plan view thereof.

The broken line showing of the outlet port is for the purpose of illustrating environmental structure and forms no part of the claimed design.
